UNITED STATES PATENT OFFICE

HENDRIK J. VAN DER BIJL, OF NEW YORK, N. Y., ASSIGNOR TO WESTERN ELECTRIC COMPANY, INCORPORATED, OF NEW YORK, N. Y., A CORPORATION OF NEW YORK

ELECTRON-DISCHARGE DEVICE AND METHOD OF MAKING THE SAME

Application filed December 4, 1918. Serial No. 265,222.

This invention relates to electron discharge devices such as may be employed for amplifiers, detectors, repeaters and the like and has for an object to provide a simple and efficient disposition of the electrodes.

This object is attained by symmetrically disposing a grid electrode around a cathode and by symmetrically disposing an anode around the other two electrodes. The electrons may then pass from the cathode to the anode in numerous radial directions, the radial paths being intercepted and efficiently controlled by means of the grid electrode which surrounds the filament or cathode.

The above arrangement of electrodes may be mounted in a very simple manner without the use of glass arbors by employing comparatively heavy supporting wires which are connected at one end to the electrodes and at their other ends to the so-called press or squash which is the termination of the inwardly projecting tubular portion in which the lead wires are sealed.

The specific forms of electrodes chosen by way of illustration are a straight filamentary cathode surrounded by a helical grid and a cylindrical anode. Another feature of the invention has to do with the assembly of these electrodes according to which the anode is slipped over the grid, the filament being mounted along the axis of the grid. In case the grid is mounted first, the anode is apertured so that it may pass the grid support, the filament being finally mounted in position.

For further details of the invention reference may be made to the drawing in which the single figure indicates in perspective a vacuum tube constructed in accordance with the present invention, this tube being connected in a conventional repeater circuit.

Referring to the drawing the vacuum tube 1 comprises the usual inwardly projecting tubular portion 2, which terminates in the press or squash 3, in which the various supporting and leading-in wires are sealed. The cathode in this case is shown as taking the form of a straight wire 4, which is supported by the relatively heavy wires 5 and 6, one end of each of which supports the filament and

the other ends being embedded in the squash. Surrounding the filament 4 is a helical grid 7 which is supported by a relatively heavy wire 8 embedded at its lower end in the squash and projecting through an aperture 9 which may extend the full length of the cylindrical anode 10. The anode 10 is supported by the heavy wires 11 and 12, the latter being connected with the leading-in wire 13.

If the vacuum tube is operated on an aeroplane or elsewhere under conditions such that it is subject to vibration, it is desirable to prevent an erratic operation due to a change in the relative position of the electrodes. The mounting provided for the electrodes prevents such vibration and this is particularly true with regard to the grid which is reinforced for instance by the wire or rod 22 to which the turns of the grid are fastened, viz, by welding.

During the evacuation of the vacuum tube 1 it is customary to heat the electrodes to a high temperature to expel occluded gases therefrom. This heating of the plate or anode causes it to vaporize to a slight extent, a metallic deposit being formed on the inner wall of the glass bulb. If the anode 10 formed a complete surface immediately above the top of the press 3, a metallic deposit would be formed thereon. This would metallically and hence electrically connect all the lead wires which would consequently be short circuited. This is prevented according to the present invention by removing that portion of the anode 10 immediately above the lead wires where they emerge from the press. This removal forms the slot 9.

In assembling the electrodes, it is preferred to mount the grid in position first, then to position the anode about the grid. The slot 9 permits the anode 10 to be moved longitudinally over the grid, either the wire 5 or 6 passing along the slot for this purpose. The filament can be inserted before or after the anode has been mounted.

By way of illustration, the vacuum tube 1 is shown as connected in a conventional repeating and amplifying circuit, although it is obvious that this vacuum tube device may

be employed in many other types of circuits. The circuit illustrated in the drawing comprises an incoming line 14, which supplies comparatively weak impulses to be amplified to the input circuit 15 of the vacuum tube, 5 the output circuit 16 thereof supplying the amplified impulses to the outgoing line 17. The battery 18 makes the potential of the grid negative with respect to that of the filament; the battery 19 lights the filament; and battery 20 impresses a positive potential on the anode through the choke coil 21.

While the drawing shows the grid and anode in the shape of circular cylinders the 15 invention is not restricted thereto as other types of cylinders may be employed.

What is claimed is:

1. A vacuum tube device comprising a press 20 a cathode, an anode surrounding said cathode, the inner surface of said anode being substantially concentric with said cathode, and supporting wires fastened at one extremity to said electrodes and embedde at their other extremities in said press, said wires 25 forming the sole supporting means between said electrodes and said press and comprising means for establishing a potential difference between the electrodes.

2. A vacuum tube device comprising a 30 press, a cathode, a grid surrounding said cathode, an anode surrounding said grid and cathode, and supporting wires connected at one extremity to said electrodes and at their other extremities to said press, said wires 35 forming the sole supporting means between said electrodes and said press.

3. A vacuum tube device comprising an inwardly projecting tubular portion terminating in a press, a cathode, an anode, the inner 40 surface of said anode being substantially concentric with said cathode, said electrodes being symmetrically disposed about an axis substantially at right angles to the axis of said tubular portion, and supports for said electrodes, said supports comprising means for establishing a potential difference between 45 said electrodes.

4. A vacuum tube device comprising a tubular portion terminating in a press, a cathode, 50 a grid surrounding said cathode, an anode surrounding said grid and cathode, said electrodes being symmetrically disposed about an axis substantially at right angles to the axis of said tubular portion, and means for supporting said electrodes.

5. A vacuum tube comprising a tubular portion terminating in a press, a cathode, a grid surrounding said cathode, an anode surrounding said grid and cathode, said electrodes being symmetrically disposed about an axis at right angles to the axis of said tubular portion, and heavy wires for supporting said electrodes, said wires being connected 65 at one end to said electrodes and being em- bedded at their other ends in said press.

6. A vacuum tube device comprising a tubular portion terminating in a press, a helical grid, an anode surrounding said grid, a straight filament within said grid and extending along the axis thereof, said electrodes being symmetrically disposed about an axis 70 at right angles to the axis of said tubular portion, and supporting wires connected at one end to said electrodes and having their other ends embedded in said press.

7. A vacuum tube device comprising a press, a helical grid extending substantially parallel to the top of said press, a filament within said grid, a cylindrical anode outside of said grid, and lead wires in said press for 80 said electrodes, said anode having a slot at the side thereof adjacent said press.

8. A vacuum tube comprising a press, anode, cathode and grid electrodes adjacent 85 said press, and metallic means connecting said electrodes and said press, and forming the sole support for said electrodes.

9. A vacuum tube comprising a press, anode, cathode and control electrodes adjacent 90 said press, and a plurality of supporting wires connecting said press and said electrodes, at least two of said wires supporting said cathode, at least two of said wires supporting said anode, and at least one of said wires supporting said control electrode. 95

10. A vacuum tube device comprising a press, a helical electrode extending substantially parallel to the top of said press, means for supporting said electrode, and a wire fastened to the turns of said electrode. 100

11. A vacuum tube device comprising a press, a helical electrode extending across the top of said press, means for connecting said electrode to said press, and means for preventing vibration of said helical electrode. 105

12. A vacuum tube device comprising a press, a helical grid extending across the top of said press, a wire extending across the turns of said grid and welded thereto, an anode, and a cathode associated with said grid. 110

13. The method of making a vacuum tube having a cylindrical grid, a cylindrical anode and a filament which comprises providing an aperture in the wall of said anode, in relatively moving the support for one of said other electrodes with respect to and in said aperture, and in fastening said electrodes in position. 115

14. The method of making a vacuum tube having a grid, a cylindrical anode and a filament which comprises providing an aperture in the wall of said anode, in supporting one of said other electrodes, in moving said aperture across the support to position the electrodes, and in fastening said electrodes in position. 125

15. A vacuum tube comprising a press, anode, cathode, and grid electrodes adjacent 130

5 said press, said electrodes being symmetrical-
ly arranged about an axis transverse to the
longitudinal axis of said press, and metallic
means connecting said electrodes and said
press, and forming the sole support for said
electrodes.

10 16. A vacuum tube comprising a press,
anode, cathode and grid electrodes adjacent
said press, said electrodes being arranged sub-
stantially concentrically with each other, and
metallic means connecting said electrodes and
said press, and forming the sole support for
said electrodes.

15 17. A vacuum tube comprising a press, a
cathode, a helical grid surrounding said cath-
ode, an anode surrounding said grid, and me-
tallic means connecting said electrodes and
said press and forming the sole support for
said electrodes.

20 18. A vacuum tube comprising a press, an
electrode extending across the top of said
press, said electrode having a discontinuous
surface at the portion thereof adjacent the
top of said press, a second electrode opera-
tively associated with said first electrode, and
a plurality of lead wires extending from said
press, said lead wires supporting said elec-
trodes and comprising means for establishing
a potential difference between said electrodes.

25 19. A vacuum tube comprising a stem,
anode, cathode and grid electrodes adjacent
said stem, said electrodes being arranged sub-
stantially concentric with each other and me-
tallic means for supporting said electrodes
from said stem.

30 20. An electron discharge device compris-
ing a vessel having a stem, a cylindrical anode,
a cathode, a grid interposed between said cath-
ode and anode, said last named electrodes be-
ing arranged coaxial with said anode, and
metallic supporting connections between said
stem and said electrodes.

35 21. An electron discharge device compris-
ing a vessel having a stem, a cylindrical anode
40 supported by said stem, a filamentary cathode
coaxial with said anode, a helical control elec-
trode interposed between said cathode and
anode, and metallic supporting connections
between said stem and said control electrode
and cathode.

45 22. An electron discharge device compris-
ing a vessel having a stem, a cylindrical anode
having a metallic supporting connection with
said stem, a filamentary cathode and helical
50 grid within said anode, and metallic support-
ing connections between said electrodes and
said stem.

55 23. An electron discharge device compris-
ing a vessel having a stem, a pair of support-
ing wires secured in and extending above
60 said stem, a filament extending between said
wires, a helical grid, and a substantially cy-
lindrical anode, said last-named cathode and
grid being coaxial with said filament.

65 24. A vacuum tube comprising a stem, con-

centric anode, cathode and grid electrodes
having their axes substantially at right angles
to the axis of said stem, and metallic means
for supporting said electrodes from said stem.

In witness whereof, I hereunto subscribe
my name this 21st day of November, A. D., 70
1918.
